TOILET PREPARATION

George Sperti, Cincinnati, Ohio, assignor to The
Institutum Divi Thomae Foundation, Cincinnati, Ohio, a corporation of Ohio

No Drawing. Application June 19, 1939,
Serial No. 279,998

10 Claims. (Cl. 167—91)

This invention relates to cosmetic or detergent preparations intended for external or topical application, and more particularly to the effect of such preparations on the respiration of the tissues to which they are applied. The field of application of the invention thus includes toilet preparations, such as lotions, creams, oils, and detergents, such as toilet soaps, mouth washes and tooth pastes, etc., all of which are to be understood as included within the terms "cosmetics" and "detergents" as employed herein and in the appended claims. This application is a continuation in part of my prior application Serial No. 184,338, filed January 10, 1938.

It is known that human skin respires, taking up oxygen from the surrounding atmosphere and from the blood stream apparently as a function of the cell life in the skin tissue. It is furthermore known that one difference between old skin and young skin is that the rate of respiration declines with age, young skin respiring or breathing more rapidly than old skin and absorbing greater quantities of oxygen. Moreover, it appears that skin which has not been exposed to some stimulating influence, such as light, wind, massage, etc., shows depressed respiration.

Heretofore, as far as I am aware, no practicable way has been devised to stimulate skin respiration by the application of cosmetics. In fact, it has been found that all cosmetics and detergents tested, although they may possess other beneficial properties, have the undesirable action of depressing tissue respiration, thus exaggerating the normal decline in respiration which takes place with increasing age as well as the depressed respiration existing under ordinary conditions. For a study of this nature, it is desirable in order to obtain scientific determinations of respiration to measure oxygen consumption of the tissues by suitable manometric methods, such as disclosed for example in the standard work "Manometric Methods" by Malcolm Dixon; the so-called "direct method" of Warburg is well adapted for such measurements.

Two procedures are available: (1) "in vitro" experiments in which the substance tested is added to the skin fragments in the manometer flask; (2) "topical application" experiments in which the cosmetic is applied to the skin for a given period, any excess of cosmetic being removed before excision of the skin. Both types of experiments are controlled with normal untreated skin from the same animal or person, and, in the second case, the control skin is rubbed the same length of time as the experimental to eliminate stimulation due to massage. While the first method will reveal acute toxic manifestations, the second method more nearly reproduces the conditions found in practice. De-

pression is encountered by both methods, as shown by the examples given below. Creams are usually less active depressants than are soaps and lotions. These depressant effects of cosmetics may be attributed to a number of causes each of which is probably operative to a variable degree. Among them are the previously demonstrated adverse effects of antiseptics, fatty acids, and unphysiological pH.

10 As disclosed in my copending application Serial No. 280,000, filed June 19, 1939 concurrently herewith, it has been found that agents having the property of stimulating tissue respiration can be produced in a number of ways, and as illustrated 15 by the examples below, the addition of such stimulating agents in suitable amounts to cosmetics and detergents has the effect of counteracting the usual depressant effects thereof. While the particular source of and procedure for 20 obtaining such respiratory stimulating agents is not a part of the present invention, suitable illustrative procedures are given by way of example.

Example 1

25 Yeast is a convenient source of material which can readily be processed and which provides a substantial yield of the respiratory stimulating substances. The following procedure may be followed for producing the crude preparation.

30 Seven pounds of fresh Fleischmann's bakers yeast were extracted with 2.5 liters of 95% ethyl alcohol for four hours at a temperature of 60-70° C. with constant mechanical stirring. The alcohol lost during the extraction was continually replaced. The mixture was then filtered through a Büchner funnel and the residue reextracted with 2.5 liters of 50% ethyl alcohol under the same conditions. The extracts were filtered 35 until clear and the residues discarded. The combined filtrates contained a crude respiratory stimulating substance which was obtained in solid form by evaporating the combined filtrates to 400 cc. under reduced pressure at a temperature not greater than 60° C. and then evaporating the extract to dryness at 70° C. This crude substance when tested for its capacity to stimulate cellular respiration according to the manometric methods referred to above, showed stimulation with respect to both rat skin and human skin.

40 The crude extract described above is suitable for use in some cases, as in soap, but may have an objectionable odor or color when used in other 45 preparations, such as face creams, mouth washes, etc. For such purposes it is therefore desirable to refine the crude extract. This extract is substantially free of protein but contains small amounts of certain dissolved protein substances 50 which it is first desirable to remove. This may

readily be accomplished by precipitation with a suitable precipitating agent, barium hydroxide being well suited because excess barium can readily be removed. The following procedure is illustrative: To 200 cc. of the extract were slowly added with constant stirring 800 cc. of a hot saturated solution of barium hydroxide. A volume of 95% ethyl alcohol, equal to twice the volume of the extract plus the barium hydroxide, was then added with constant stirring which was continued for ten minutes after the addition had been completed. The mixture was allowed to stand for ten minutes longer and filtered. To remove excess barium, the filtrate was saturated with carbon dioxide by bubbling it through the liquid for one hour, after which the mixture was concentrated under reduced pressure to a volume of 150 cc. at 30-55° C. and was filtered through a Büchner funnel to remove the barium carbonate precipitate. The filtrate was then warmed to 60° C. on a water bath and 2.5 N. sulphuric acid was added slowly with constant stirring until all the barium was precipitated, 22 cc. of acid being required. The barium sulphate was filtered out, leaving a perfectly clear filtrate which was evaporated to dryness at 70° C. This material showed definite stimulation of respiration on skin of the order of 40-65%.

For further refinement of the filtrate described immediately above, this filtrate was treated with acetone by adding three liters of acetone slowly, with shaking, to 150 cc. thereof, allowing the mixture to stand at room temperature for seventy-two hours, after which the acetone solution was decanted from the red oily precipitate. This precipitate, after washing with acetone and drying at 70° C. showed marked stimulation on skin.

A similar product was also obtained from the precipitate from the original barium hydroxide precipitation. To remove the water soluble constituents, this precipitate was stirred with a 100 cc. portion of distilled water at room temperature and filtered. After this operation had been repeated three times, the combined washings were saturated with carbon dioxide, the solution reduced in vacuum at 40° C. to a volume of 54 cc., and the barium carbonate filtered off and discarded. The clear, reddish filtrate was then heated to 60° C. and 2 cc. of 2.5 N. sulphuric acid were slowly added with stirring, after which the barium sulphate formed was allowed to settle and filtered off. The solution was evaporated to dryness at 70° C. and the resulting product showed definite stimulation of skin respiration.

Example 2

A simpler method of refining the crude alcoholic yeast extract described in the foregoing example is by the use of an adsorbent, such as charcoal, diatomaceous earth, etc., as a refining agent. The above described method of extracting Fleischmann's bakers yeast with 95% ethyl alcohol and then with 50% ethyl alcohol and then combining and concentrating the extracts may be followed to obtain the crude extract. The following procedure illustrates the refinement of this crude extract by means of activated charcoal.

The concentrate was divided into three portions and dried in the oven at 50-55° C. The dry material was dissolved in distilled water (sample A), 25 per cent ethyl alcohol (sample B) and 40 per cent ethyl alcohol (sample C) to a concentration of approximately 50 mg. per cc. The three solutions were then further divided into 3

parts to decolorize at 5-8° C. (sample 1), room temperature, which was about 25° C. (sample 2), and 60° C. (sample 3). The solution was either heated or cooled to the proper temperature and approximately one-tenth its weight of charcoal added. After stirring well for a few minutes, the material was filtered through a Büchner funnel. The charcoal was then removed from the filter, stirred in the same solvent at the same temperature as the previous treatment, and again filtered to remove adhering material, and the washings were added to the original filtrate.

The original crude, after drying and making up to the proper concentration with the various solvents, was dark brown in color and had an objectionable yeast-like odor. After treatment with the charcoal, in every case, the color became lighter and the odor less disagreeable. The water decolorizations were more effective in removing the color and odor than the alcoholic ones, and the 5-8° C. and 60° C. treatments were better than the room temperature decolorizations. Two or three successive treatments of this water solution at 60° C. gave water-white and nearly odorless preparations.

For testing the dried samples were made up to a concentration of 50 mg. per cc. or, if the quantity of material was small, as in the case of the charcoal adsorbed material, as high a concentration as possible was used. The pH was determined by the glass electrode and adjusted to 7.3 with sodium hydroxide or hydrochloric acid for testing on yeast and skin respiration. If the pH of the samples was between 5.6 and 7.3 they were sterilized at 15 pounds pressure for 15 minutes before adjusting the pH. It had been found earlier that the respiratory stimulating factors may be sterilized within this pH range without loss of activity. Samples, the initial pH of which lay outside the above range, were adjusted to pH 7.3 before sterilization.

The decolorized filtrates were tested on skin by the manometric method referred to above. While all of the samples showed stimulation of skin respiration, those giving the best results were as follows:

50	Sample	Original pH	Original conc., mg. per CC.	Skin activity	
				Per cent stimulation	Conc., mg. per cc. at pH 7.3
	A-3-a	6.6	50.0	110	7.26
55	B-1-a	5.95	50.0	106	10.0
	C-1-a	5.95	50.0	52	6.67
				47	10.0
				41	10.0

Example 3

Ten pounds of fresh beef spleens were skinned, cut into small pieces and washed with cold water to remove blood. The pieces were ground in a meat grinder and extracted with 4 liters of distilled water for one hour at 45° C. with constant mechanical stirring. The material was filtered through cheesecloth and muslin and squeezed as dry as possible. To 3 liters of this filtrate was added 12 liters of 95% ethyl alcohol to give a final alcohol concentration of 80%. This caused the formation of a precipitate which was filtered off on a Büchner funnel and was then extracted with 1.5 liters of water. The material was then filtered on a Büchner funnel and the filtrate was concentrated to small volume in vacuo at not greater than 65° C. and brought to dryness in an

oven at 50° C. In manometer tests this material showed stimulation of skin respiration of 42%.

Respiratory stimulating agents as above described are soluble in water and dilute alcohol and stable to heat and in the presence of alkalies and moderately strong acids. Hence they are well adapted for use in cosmetics and detergents, although it will be understood that within the broad aspect of the invention any other suitable respiratory stimulating agent may be substituted therefor. The amount to be used depends somewhat on the potency of the specimen used, but is primarily controlled by the extent to which stimulation is desired in a cosmetic preparation for general distribution and also on the extent of the depressing action of the preparation in which it is used.

Examples of typical cosmetic and detergent preparations containing a respiratory stimulating agent (R. S. F.). It will be understood that the amount of R. S. F. used in these examples is illustrative only and that either more or less may be used depending on the effect desired in any particular case.

Example 4.—Vanishing cream

	Grams
Stearic acid	180
Caustic soda	9
Glycerine	50
Water (distilled)	750
Perfume	11
R. S. F.	10

Example 5.—Cold cream

	Grams
Liquid paraffin	300
Sol. white paraffin	200
White beeswax	100
Stearic acid	14
Triethanolamine	6
Borax	10
Water (distilled)	300
Perfume	5
R. S. F.	10

Example 6.—Soap

	Grams
Soap stock	920
Sodium hydroxide	120
R. S. F.	10
Perfume	10
Water	150

Example 7.—Emollient skin balm

Gum karaya	g.	3.5
Water (distilled)	cc.	108.6
Glycerine	cc.	18.9
95% alcohol	cc.	76.1
Salicylic acid	g.	0.1944
Carbolic acid	g.	3.240
Powdered soap	g.	3.0
R. S. F.	g.	2.10

Perfume

Example 8.—Skin fresheners

	Grams
Alum	40
Borax	30
Glycerine	30
Alcohol	200
Orange flower water	300
Rose water	400
R. S. F.	10

The addition of the respiratory stimulating agent may be made in any suitable manner according to the nature of the preparation. For example, the agent may be dissolved in a small

quantity of a suitable solvent such as dilute alcohol or water and then mixed with a skin cream, lotion, soap, etc., the solvent being thereafter evaporated off if desired. These methods are only illustrative, however, and can be varied to suit manufacturing procedures and conditions in any particular case.

Carefully controlled manometer tests have demonstrated that these cosmetic preparations (creams, lotions and toilet soaps) containing the respiratory stimulating agent do increase skin respiration as compared with the same cosmetics without any such agent. Thus the use of this agent in cosmetics in whole or in part prevents the respiration of the skin, which is depressed under the usual living conditions, from further depression by use of the cosmetics, as shown by the following examples:

Example 9.—Topical application of lotion to human skin

Three areas of skin in the same region were selected on a patient twenty to thirty years of age. One area (control) was rubbed with Ringer solution. The second area was rubbed with a mixture of Ringer solution and a commercial lotion, and the third was rubbed with a mixture of Ringer solution containing 39.4 mg. per cc. of an R. S. F. preparation and the same amount of lotion. The skin areas were then removed and tested for respiration in the manometer.

The results of the experiments are as follows:

	Flask	Time	Aver-age dry weight in grams	Aver-age total O ₂ consumed in cu. mm.	Aver-age QO ₂ in cu. mm.	Per cent decrease
Control—Ringer only		2	.0025	6.31	1.262	—
Experimental—lotion plus Ringer		2	.00185	1.89	.488	61
Experimental—lotion plus Ringer plus R. S. F.		2	.0020	3.12	.772	38

It will be seen that in this experiment enough R. S. F. was added to partially overcome the depressing action of the lotion.

Example 10.—Topical application of soap to human skin

Three areas of skin in the same region were selected on a patient twenty to thirty years old. One area (control) was rubbed with Ringer solution. The second area was rubbed with a mixture of Ringer solution and soap, and the third was rubbed with a mixture of Ringer solution containing 39.4 mg. per cc. of an R. S. F. preparation and the same amount of soap. The skin areas were then removed and tested in the manometer.

The results of the experiments are as follows:

	Flask	Time	Aver-age dry weight in grams	Aver-age total O ₂ consumed in cu. mm.	Aver-age QO ₂ in cu. mm.	Per cent decrease
Control—Ringer only		2	.0024	5.05	1.067	—
Experimental—soap plus Ringer		2	.00125	1.37	.547	49
Experimental—soap plus Ringer plus R. S. F.		2	.0011	1.89	.883	17

In this experiment sufficient R. S. F. was added to overcome about two-thirds of the depressing action of the soap.

Example 11.—Topical application of facial cream to human skin

Three areas of skin in the same region were selected on a patient twenty to thirty years old. One area (control) was rubbed with Ringer solution. The second was rubbed with a mixture of facial cream and Ringer solution, and the third with a mixture of Ringer solution containing 39.4 mg. per cc. of an R. S. F. preparation and the same amount of cream. The skin areas were then removed and tested in the manometer.

The results are given in the following table:

Flask	Time	Average dry weight in grams	Average total O ₂ consumed in cu. mm.	Average QO ₂ in cu. mm.	Percent decrease
Control—Ringer only...	2 hours	.0020	9.47	2.366	-----
Experimental—cream plus Ringer	2	.0014	5.96	2.117	6
Experimental—cream plus Ringer plus R. S. F.	2	.0017	8.00	2.361	0.3

In this experiment the addition of R. S. F. completely overcame the depressing action of the cream.

It will be understood that changes may be made in the procedures, proportions, and other details set forth above, and that respiratory stimulating agents may be obtained from other sources and by other methods than those particularly described. These particulars are set forth herein by way of illustration only and many such changes will now suggest themselves to those skilled in the art without departure from the spirit of the invention. Hence reference should be had to the appended claims to define the limits of the invention.

What is claimed is:

1. A toilet preparation for topical application comprising a preparation which depresses the respiration of the tissue to which it is applied combined with a respiratory stimulating agent which stimulates the tissue respiration as determined by manometric measurements and thereby compensates at least in part for the depressing effect of said preparation.

2. A toilet preparation for topical application comprising a respiratory stimulant capable of stimulating the respiration of tissue to which it is applied as determined by manometric methods combined with a saponaceous agent inert to said stimulant.

3. A new composition of matter for topical application for cosmetic purposes comprising a cosmetic which depresses tissue respiration having incorporated therein a respiratory stimulating factor capable of stimulating tissue respiration as determined by manometric measurement, the cosmetic being compatible with said respiratory stimulating factor to retain and make available its respiration stimulating properties upon use of said cosmetic.

4. A new composition of matter for topical application for cosmetic purposes comprising a soap which depresses tissue respiration having incorporated therein a respiratory stimulating factor capable of stimulating tissue respiration

as determined by manometric measurement, the soap being compatible with said respiratory stimulating factor to retain and make available its respiration stimulating properties upon use of said soap.

5. A new composition of matter for topical application for cosmetic purposes comprising a skin cream which depresses tissue respiration having incorporated therein a respiratory stimulating factor capable of stimulating tissue respiration as determined by manometric measurement, the skin cream being compatible with said respiratory stimulating factor to retain and make available its respiration stimulating properties upon use of said skin cream.

10 6. A new composition of matter for topical application for cosmetic purposes comprising a lotion which depresses tissue respiration having incorporated therein a respiratory stimulating factor capable of stimulating tissue respiration as determined by manometric measurement, the lotion being compatible with said respiratory stimulating factor to retain and make available its respiration stimulating properties upon use of said lotion.

7. A new composition of matter for topical application for cosmetic purposes comprising a cosmetic which depresses tissue respiration having incorporated therein a respiratory stimulating factor capable of stimulating tissue respiration as determined by manometric measurement, the cosmetic being compatible with said respiratory stimulating factor to retain and make available its respiration stimulating properties upon use of said cosmetic, said respiratory stimulating factor comprising the concentrated water-soluble constituents of cellular matter.

30 8. A new composition of matter for topical application for cosmetic purposes comprising a cosmetic which depresses tissue respiration having incorporated therein a respiratory stimulating factor capable of stimulating tissue respiration as determined by manometric measurement, the cosmetic being compatible with said respiratory stimulating factor to retain and make available its respiration stimulating properties upon use of said cosmetic, said respiratory stimulating factor comprising the concentrated water-soluble constituents of yeast cells.

40 9. A new composition of matter for topical application for cosmetic purposes comprising a cosmetic which depresses tissue respiration having incorporated therein a respiratory stimulating factor capable of stimulating tissue respiration as determined by manometric measurement, the cosmetic being compatible with said respiratory stimulating factor to retain and make available its respiration stimulating properties upon use of said cosmetic, said respiratory stimulating factor comprising the acetone-insoluble portion of the water-soluble constituents of cellular matter.

50 10. A new composition of matter for topical application for cosmetic purposes comprising a cosmetic which depresses tissue respiration having incorporated therein a respiratory stimulating factor capable of stimulating tissue respiration as determined by manometric measurement, the cosmetic being compatible with said respiratory stimulating factor to retain and make available its respiration stimulating properties upon use of said cosmetic, said respiratory stimulating factor comprising the acetone-insoluble portion of the water-soluble constituents of yeast cells.
